W. ALLWARD

DRILL HOLDING MAGAZINE

Filed July 5, 1922

Inventor
Walter Allward

By Fred G. Detrich & Co
Attorneys

UNITED STATES PATENT OFFICE.

WALTER ALLWARD, OF VANCOUVER, CANADA.

DRILL-HOLDING MAGAZINE.

Application filed July 5, 1922. Serial No. 572,971.

To all whom it may concern:

Be it known that I, WALTER ALLWARD, citizen of the Dominion of Canada, residing at Vancouver, in the Province of British Columbia, Canada, have invented certain new and useful Improvements in Drill-Holding Magazines, of which the following is a specification.

This invention relates to a magazine for holding small dental drills or the like articles, and for presenting one of each kind in a readily accessible manner for use. Dentists at present usually retain their supply of small drills, which are ready for use, in vertically disposed apertures in a revolvable stand, from which they can be selected as required, but as the stand is designed to hold a number of each kind of drill, and all are exposed to view, difficulty is experienced in selecting the drill wanted from so many exposures.

In the device which is the subject of this application, a considerable number of drills of each kind are retained, one above the other, in separate receptacles, from which the lower one only of each kind, is projected through an aperture for inspection and withdrawal.

Each row of delivery apertures is also provided with a retaining clip for number bearing tickets, that the drills in the magazine may be identified by number, if not by inspection.

The invention is particularly described in the following specification, reference being made to the drawings by which it is accompanied, in which:

Fig. 1 is a perspective view of the magazine, a portion of the casing being removed.

Fig. 2 is a vertical section on the plane 2—2, and

Fig. 3 is a perspective view of the drill projector.

The magazine comprises a substantially rectangular box-like casing 2 of thin sheet metal, having a cover 3 closing the open top, which cover is preferably hinged to the back edge of the casing.

In the middle of the front wall of this casing, near the bottom, is an aperture to receive the drill projecting plunger 12. Above this plunger 12, is a row of small apertures 4, adapted to freely pass a drill, and above that is another row of similar apertures 5, spaced between those 4.

The casing is provided with small feet 6,

preferably of rubber or rubber faced. A block 7 which fits the casing 2 in depth and width is secured within it against its front face to leave a space between its back and the back of the casing to allow for the movement of the drill projector.

In this block 7 a number of drill holding slots 8 are cut to register with the apertures 4 of the casing and extending from the top 65 of the block to the level of these apertures. In length these slots 8 are adapted to receive the longer drills.

Spaced between the slots 8, similar slots 9 adapted to hold the shorter drills, extend 70 from the top of the block to the level of the higher row of apertures 5.

When the block 7 is secured within the casing 2, the slots 8 and 9 form separate receptacles for a number of drills of each 75 kind, and the bottom drill of each receptacle may be projected through the apertures 4 and 5 of the casing 2.

The means by which the bottom drill in each receptacle 8 and 9 is projected through the apertures 4 and 5 respectively, comprises a bar 10 adapted to slidably fit a transverse groove extending along the back of the block 7 at the level of the slots 8 and normally projecting into the back end of the 85 slots. The back edge of this bar 10 is upwardly turned and in the backwardly turned portion, is secured a series of pins 11 fitting holes drilled through the block from the back into the bottom of each slot 9. As in 90 the case of the bar 10, these pins 11 normally project a short distance into the slots 9 to project the front end of each bottom drill through its aperture 5 of the casing.

The plunger 12 by which movement of the projector is effected slidably fits the aperture of the casing, and a corresponding aperture in the block 7 with which it registers. Within the block, the plunger is reduced in diameter to receive a spring 13 coiled on it 100 between the shoulder of the reduction, and a retaining washer plate 14 through which the reduced portion of the plunger passes before attachment of it to the bar 10. This spring 13 normally holds the bar 10 and its attached pins 11 at the inner limit of its movement.

In use the magazine receptacles 8 and 9 are charged respectively with the longer and shorter drills, each receptacle being reserved for drills of one kind. As the projecting bar 10 for the receptacles 8 and the pins 11

attached to that bar project into the after end of each slot or receptacle 8 and 9 at the level of the bottom, the bottom drill in each receptacle will rest with its after end on the 5 bar or on one of the several pins 11 as the case may be. When the plunger 12 is pressed back against the resistance of its spring 13, the after end of the bottom drill of each receptacle will fall to the bottom and in the 10 path of movement of the bar 10 and pins 11, and on relieving the pressure on the plunger, the spring will exert its effort, and the bottom drill of each receptacle 8 and 9 will be projected through their apertures 4 and 5 in the magazine casing, a sufficient distance 15 to allow of inspection of the drill ends, and withdrawal of such drill as may be wanted.

The user is thus not confused in his inspection by the presence of a number of 20 drills of the same kind on exhibit, as is the case with the drill magazine in present use.

As used, a drill may be discarded for 25 cleaning and sterilization in readiness for another patient, and for sharpening if necessary, and after treating, such drills are returned to their respective receptacles.

Obviously, the bar 10 may be channel shaped and the back of the block be transversely grooved to receive the upper edge of 30 the channel bar in alignment with the several shorter drill slots 9, in the same manner as the bar 10 acts in relation to the longer drill slots 8, but when this is done the drills, being short, are liable to pass 35 the lower drill of each in the several series of receptacles aligned with one of their respective rows of apertures of the casing, and means for projecting the front end of the bottom drill in each receptacle through the 105 several rows of apertures in the casing.

The block 7 may be made in any convenient manner, but is preferably made of wood or other suitable material, and the slots 8 and 9 are lengthwise cut by saws, and thereafter strips are inserted, and glued or otherwise secured in the lower part of each slot 40 to limit the depth of the drill receptacles 8 and 9 at level of the apertures 4 and 5.

With the small dental drills difficulty may be experienced in identifying by inspection 45 the particular drill wanted. A card holding clip 15 is therefore secured to the casing 2 above each row of drill apertures 4 and 5 and extending along the width of the casing. Within these clips 15, cards may be endwise 55 inserted bearing a number by which the drills may be known.

Having now particularly described my invention, I hereby declare that what I claim as new and desire to be protected in by 60 Letters Patent, is:

1. A magazine for small drills and like instruments having a plurality of vertically positioned receptacles, the bottom of such receptacles constituting a support for holding the drills placed therein in substantially

horizontal position, one above the other, the base of one series of receptacles being in a plane below the base of the other series of receptacles, the magazine including a front wall having a plurality of rows of apertures, one row of said apertures aligning with the base of one of the series of receptacles and the other row of said apertures aligning with the other series of receptacles, and means for simultaneously projecting one 70 end of the bottom drills in each series of drill holding receptacles endwise from their respective receptacles. 75

2. A magazine for small drills or the like instruments, said magazine having a plurality of series of receptacles each adapted to retain the drills horizontally disposed one above the other, means for retaining all but the bottom drill in each receptacle against endwise movement therefrom, and manually operated means for projecting the bottom drill in each of the plurality of series of receptacles a short distance endwise from it. 80

3. A magazine for small drills or the like instruments, said magazine comprising, a substantially rectangular casing having an open top, said casing having a plurality of rows of apertures through its front wall near the bottom, the several rows being disposed in different horizontal planes, a block 95 secured within the casing with its front face in contact with the front wall thereof, said block having several series of receptacles adapted to support a number of drills horizontally disposed one above the other, with the lower drill of each in the several series of receptacles aligned with one of their respective rows of apertures of the casing, and means for projecting the front end of the bottom drill in each receptacle through the 100 several rows of apertures in the casing. 105

4. A magazine for small drills or the like instruments, said magazine comprising, a substantially rectangular casing having a closable open top, said casing having a row 110 of apertures through its front wall, a block secured within the casing with its front face in contact with the front wall of the casing, said block having receptacles adapted to support a number of drills horizontally disposed one above the other with the lower drill of each receptacle opposite one of the apertures of the casing, means for projecting the front end of the bottom drill of each receptacle simultaneously through their corresponding apertures of the casing, said means comprising a horizontally disposed bar slidably mounted in a transverse slot along the back of the block in line with the bottom of the several drill holding receptacles and susceptible of being projected into the back of the receptacles, and means for moving the bar backward and forward. 115

5. A magazine for small drills or the like instruments, said magazine comprising a 120

substantially rectangular casing having a closable open top, said casing having two rows of apertures through the front wall, the apertures of one row being spaced between those of the other, a block secured within the casing with its front face in contact with the front wall of the casing, said block having a receptacle in alignment with each aperture of the casing and terminating thereat, the block having also a slot extending across its back in alignment with the bottom of the several receptacles of the lower row, and the upper row have holes through from the back in alignment with the bottom of each receptacle, a plunger passing through an aperture in the casing and block,

said plunger being reduced in diameter from within the casing, to the back end a plate secured to the back of the block through which the reduced end of the plunger passes, a coiled spring on the reduced portion of the plunger between the shoulder of the reduction, and the back plate, a projector bar secured to the back end of the plunger, and fitting the transverse slot of the lower row of receptacles, the back edge of the bar being upwardly turned to receive a series of pins secured in it and slidably fitting the drilled apertures of the upper row of receptacles. 25

In testimony whereof I affix my signature.

WALTER ALLWARD.
